UNITED STATES PATENT OFFICE

2,688,892

TREADLE-OPERATED BENCH VISE

George G. Benac, Gary, Ind., assignor to United States Steel Corporation, a corporation of New Jersey

Application November 20, 1953, Serial No. 393,456

4 Claims. (Cl. 81—17)

1

The present invention relates generally to vises and more particularly to a foot-operated vise.

The primary object of the invention is to provide a vise having jaws which may be rapidly opened or closed by means of foot pressure on a treadle bar.

It is a further object of the invention to provide a foot-operated vise having an improved linkage arrangement between the treadle bar and the jaws of the vise whereby pressure applied by the vise jaws is not only maintained uniformly but is increased after the force depressing the treadle bar is removed.

The nature of the invention and its distinguishing features and advantages will be fully apparent from the following detailed description and appended claims when read in connection with the accompanying drawing in which:

Figure 1 is a side elevational view showing the vise in open position;

Figure 2 is a view similar to Figure 1 but shows the vise in closed position; and

Figure 3 is a horizontal sectional view taken on the line III—III of Figure 2.

Referring more particularly to the drawing, reference numeral 2 designates a workbench of the conventional type having mounted thereon the improved vise of my invention which is designated generally by the reference numeral 4. The vise 4 may be mounted on a stationary support member 6 which is bolted or otherwise attached to the top of the bench 2. A fixed jaw 8 is rigidly attached by bolts 10 to the top of the stationary support 6. The movable portion of the vise is made up of a substantially vertically disposed leg 12 having a movable jaw 14 bolted or otherwise rigidly affixed to its upper end opposite the fixed jaw 8. The leg 12 is pivoted to the stationary support member 6 below the level of the bench surface by means of a transverse pin 16. The bottom portion of the leg 12 is provided with a cam surface 18 which is engaged by a cam roller 20 rotatably mounted on a foot-operated lever 22.

The lever 22 is made up of two articulated treadle and bearing arms 23 and 26, each of which comprises parallelly spaced bars that straddle the lower end of the leg 12 adjacent the cam surface 18. The spaced bars of the treadle arm 23 comprise treadle portions 24 and are hinged in end-to-end relation to the spaced bars of the bearing arm 26 by means of a pair of axially spaced pivot pins 28. The cam roller 20 is rotatably mounted between and carried by the spaced bars of the bearing arm 26. The outer

ends of the spaced bars of the bearing arm 26 are pivotally attached to the lower end 30 of the stationary support member 6 by means of a common pivot pin 32. A foot plate 34 is mounted transversely across the tops of the free ends of the treadle portions 24 with a portion thereof extending laterally beyond one of the treadle portions, as best seen in Figure 3.

A ratchet 36 is rigidly mounted on the stationary support member 6 by means of a pair of arms 37 and depends vertically between the treadle portions 24 of the arm 23 adjacent the lower end of the arm 12 opposite the cam surface 18. The ratchet 36 has a curved and toothed face whose radius of curvature extends to the pivot pin 32. A pawl 38 is pivotally mounted between the treadle portions 24 by means of a pivot pin 40 so as to engage the toothed face of the ratchet 36. The pawl 38 is constantly urged into engagement with the ratchet 36 by a compression spring 42 which bears against the pawl at one end and against the transverse plate 34, which extends across the treadle portions 24, at its other end.

The articulated bearing and treadle arms 26 and 23 are normally maintained in end-to-end relation in a common horizontal plane by means of a compression spring 44 which depends substantially vertically between the spaced bars of the bearing arm 26 from a cross bar 45 which is carried by and extends across the tops of the spaced bars of the bearing arm 26. Each of the spaced bars of the treadle arm 23 are provided with a projection 46 extending rearwardly of its pivot pin 28 below and parallel with the bearing arm 26. A transverse bearing plate 47 connects the free ends of the projections 46. The plate 47 is engaged by the lower end of the spring 44. A bolt 48, rigidly but adjustably attached to the cross bar 45 by means of a pair of nuts 50, the lower of which is rigidly mounted on the cross bar 45, depends a short distance into the core of the spring 44 to provide a stop for the plate 47 for limiting the upward movement of the projections 46.

A helical tension spring 52, which is attached to and extends between the upper portion of the stationary support 6 and one of the bars of the bearing arms 26 adjacent the cam roller 20, functions to urge the lever 22 to a raised position. A helical tension spring 54 is attached at one end to the upper portion of the stationary support 6 and at its other end to the arm 12 at a point below the pivot pin 16 for the purpose of

urging the movable jaw 14 away from the fixed jaw 8.

In operation, a workpiece W is positioned between the jaws 8 and 14 and the operator applies force to the lever 22 by placing his foot on the plate 34 and depressing the free end of the lever 22 causing unitary pivoting of the articulated treadle and bearing arms 23 and 26 about the pivot pin 32. As the lever pivots about the pin 32, the cam roller 20 rolls downwardly along the camming surface 18 of the leg 12. Since the arcuate movement of the roller 20 has a greater radius than the camming surface 18, the movement of the cam roller downwardly along the camming surface forces the leg 12 to pivot about the pin 16 against the force of the spring 54 thereby moving the jaw 14 toward the stationary jaw 8 thus closing the vise to grip the workpiece. As the lever 22 is so being depressed, the treadle and bearing arms 23 and 26 remain in alignment until the force exerted by the foot of the operator exceeds the compressive force of the spring 44 at which time the treadle arm 23 will pivot about the common axis of the axially spaced pivot pins 28 and will compress the spring 44. The pawl 38 travels downwardly along the ratchet 36 simultaneously with the downward movement of the free end of the lever 22 so that the jaws are kept closed after the operator removes his foot from the plate 34 by the pawl remaining engaged with the ratchet under urging by the spring 42.

After the operator has removed his foot from the plate 34 and the free end of the lever is kept depressed by action of the pawl and ratchet, the spring 44 will tend to cause the treadle and the bearing arms 23 and 26 to again resume aligned end-to-end relation thus maintaining the pressure exerted by the jaws 8 and 14 on the workpiece W.

When it is desired to open the jaws of the vise, the operator depresses the pawl 38 against the compressive force of the spring 42 to free it from engagement with the ratchet 36. The spring 52 then raises the lever 22 causing the cam roller 20 to travel upwardly along the cam surface 18. Simultaneously with the upward movement of the cam roller, the spring 54 urges the arm 12 pivotally about the pin 16 to move the jaw 14 away from the jaw 8.

While one embodiment of my invention has been shown and described, it will be apparent that other adaptations and modifications may be made without departing from the scope of the following claims.

I claim:

1. A foot-operated bench vise comprising a fixed jaw mounted on a stationary support, a leg depending below said jaw and pivoted on said support about a fixed horizontal axis, a movable jaw on the upper end of said leg cooperating with said fixed jaw, said leg having a cam surface adjacent its lower end, an operating lever pivoted on the lower end of said support in spaced relation to said cam surface, said lever having a roller thereon engaging said cam surface, said lever including a bearing bar and a treadle bar pivoted end-to-end, spring means connected with said bearing bar and said treadle bar opposing tilting movement of the treadle bar relative to the bearing bar when downward pressure is applied to the free end of the treadle bar, ratchet-and-pawl means operatively associated with said treadle bar and effective to lock the latter in the position to which it is actuated by said pressure.

2. A foot-operated bench vise as defined in claim 1 characterized by said treadle bar having a portion projecting beyond the pivotal connection between it and the bearing bar and spaced from the latter to provide a mounting for said spring means.

3. In a foot-operated vise including a fixed jaw and a movable jaw cooperating therewith, said movable jaw having a leg depending therefrom provided with a cam surface, the combination therewith of an actuating lever having a roller engaging said surface, said lever including a bearing arm and a treadle arm hinged end-to-end, spring means connected with said bearing arm and said treadle arm for normally maintaining a predetermined angularity between said portions, and ratchet-and-pawl means operatively associated with said treadle arm and effective to releasably hold it in a position of greater angularity relative to the bearing arm.

4. In a foot-operated vise the combination therewith as defined by claim 3 characterized by a supporting leg extending downwardly and rearwardly from said fixed jaw, said lever being pivoted on said supporting leg.
